UNITED STATES PATENT OFFICE.

WEBER H. ARKENBURGH, OF WESTFIELD, NEW JERSEY, ASSIGNOR TO THE HALL SIGNAL COMPANY, A CORPORATION OF MAINE.

RAILWAY-TRAFFIC-CONTROLLING SYSTEM AND APPARATUS.

1,030,961.

Specification of Letters Patent.

Patented July 2, 1912.

Application filed November 2, 1906. Serial No. 341,736.

To all whom it may concern:

Be it known that I, WEBER H. ARKENBURGH, a citizen of the United States, residing at Westfield, in the county of Union and State of New Jersey, have invented certain new and useful Improvements in Railway-Traffic-Controlling Systems and Apparatus, of which the following is a specification, reference being had therein to the accompanying drawings, forming a part thereof.

My invention relates generally to electrically controllable railway traffic-controlling apparatus and systems which employ alternating or periodic traffic-controlling electric current, and my invention particularly relates to that class of railway traffic-controlling apparatus and systems wherein traffic is controlled by the display of visual signals such as semaphores.

Still more particularly my invention relates to home-and-distant railway block signaling systems.

Generally stated, the objects of my invention are reliability and economy of operation, simplicity and economy of maintenance, and simplicity and economy of construction.

As embodied in a home-and-distant railway block signaling system, it is a more particular object of my invention to control the home-signal semaphore and the distant-signal semaphore of a given signaling apparatus by current transmitted through a track circuit, including the track rails of the block or section next in advance of such given signaling apparatus, and without dependence on any additional line-wire extending through such block or section, excepting line conductors which are employed in a general transmission line for supplying electrical energy to each signaling apparatus and track circuit of the entire system.

My invention comprises various features, all of which will appear clearly in the light of the following complete description, although I will at this point make general mention of several such features.

My invention broadly comprehends a railway traffic-controlling apparatus such, for instance, as a railway signaling apparatus arranged to control traffic along a railway track, and a triphase electric relay in control of the traffic-controlling apparatus and controllable by triphase alternating or peri-

odic electric currents or current variations in such relay and responsive to a change in the phase sequence of such triphase currents or current variations, and means for producing such triphase currents or current variations in the triphase relay and for changing the phase sequence of such currents or current variations to actuate the relay; and, more specifically, as exemplified in the illustrated embodiment, my invention comprehends a triphase relay of the rotary field induction type in the foregoing co-organization; and, still more specifically, the illustrated embodiment of my invention comprehends a triphase relay not only responsive to the aforementioned change in phase sequence of its triphase current variations, but also responsive to the given phase sequence of such current variations which obtains in the relay before such change of phase sequence is effected, and whereby the triphase relay is differentially responsive to two different phase sequences of its triphase current variations. And my invention broadly comprehends a triphase relay organized in a traffic-controlling or signaling system as above mentioned with means for effecting triphase alternating or periodic potential variations at the terminals of the relay and means for reversing the connections to two of such relay terminals to change the phase sequence of potential variations at such terminals and thus operate the relay, the relay being responsive to such change of phase sequence and, in some instances, also responsive to the phase sequence preceding such change. And my invention comprehends a triphase relay such as above mentioned organized in a system with its terminals connected with suitable sources of triphase current and with the track rails included in the connections leading to two of such terminals and with suitable switching or pole-changing means arranged to reverse the connections leading through such track rails to such two relay terminals whereby to change the phase sequence of triphase currents in such relay. And my invention broadly comprehends a home-and-distant railway block signaling system including triphase relays as above mentioned responsive to a change in the phase sequence of their triphase currents to control the distant signals, and, as exemplified in the illustrated embodiment, also re-

sponsive to the given phase sequence preceding such change whereby each relay is rendered differentially responsive to two different phase sequences of its triphase currents and is enabled to control the home signal by response to one phase sequence and to control the distant signal by response to the other phase sequence.

My invention also comprehends a traffic-controlling system comprising traffic-controlling means arranged to govern traffic along the railway track, a triphase relay, broadly new in this combination, such for instance as a rotary-field induction relay, arranged in control of the traffic-controlling means, means for supplying triphase traffic-controlling current to the relay, and means for controlling such current to govern the relay and thus control the traffic-controlling means.

My invention also broadly comprehends a railway traffic-controlling system, such for instance as a railway signaling system, comprising traffic-controlling or signaling apparatuses located at various traffic-controlling points on the railway, a multiphase traffic-controlling current transmission line such for instance as a triphase transmission line communicating with a suitable source of triphase or multiphase current and extending along the railway, triphase or other multiphase relays in control of the traffic-controlling or signaling apparatuses and in turn controllable by triphase or multiphase traffic-controlling current, for instance controllable by a change in the phase sequence of such multiphase current, means for transmitting the triphase or multiphase current of the transmission line to the multiphase relays, and means for controlling such multiphase current in each relay, for instance by changing the phase sequence thereof, so as to actuate the relay to control the traffic-controlling or signaling apparatus governed thereby. And in the illustrated embodiment my invention comprehends, as one means for transmitting the triphase or multiphase current from the transmission line to the relays, a number of triphase or multiphase transformers having secondary terminals giving triphase or multiphase potential, the terminals of each multiphase relay being connected to secondary transformer terminals all differing in phase of potential so that the relay will receive proper multiphase potential at its terminals and each relay in the illustrated embodiment being a triphase relay and having two terminals connected through the rails of the track with two secondary terminals of a distant triphase transformer and having its third terminal connected with the non-homologous secondary terminal of a triphase transformer collocated substantially with such relay; that is to say, the third terminal of the relay is con-

nected with a given secondary terminal of its collocated transformer, which given terminal is not homologous with either of the secondary terminals of the distant transformer which are connected with the other two relay terminals, whereby the third relay terminal is subjected to periodic potential not corresponding in phase with the potential at the other two terminals but in proper multiphase relation therewith. The object of this arrangement is to save an extra line wire between two traffic-controlling or signaling points when a traffic-controlling or signal-controlling multiphase relay located at one of the traffic-controlling points must be controlled by current transmitted from the distant traffic-controlling apparatus at the distant traffic-controlling point. It may be hypothetically noted that a relay might be thus controlled with multiphase current transmitted from a distant apparatus by connecting each terminal of the multiphase relay with a corresponding secondary terminal of a multiphase transformer located at the distant traffic-controlling point, but this would require a separate conductor extending along the railway for each relay terminal. The foregoing feature of my invention requires only two conductors, which may be the track rails, for connecting the terminals of the relay with secondary terminals of the distant transformer, the single remaining relay terminal or third terminal in the case of a triphase system being connected with that secondary terminal of a local transformer which is homologous with the third secondary terminal of the distant transformer to which such third relay terminal would be connected by a separate line conductor in the hypothetical case just noted. This arrangement is not limited to the triphase system, since it may be employed in other multiphase systems by connecting two relay terminals through track rails or other conductors with two secondary terminals of a distant multiphase transformer and connecting the remaining relay terminals, whether one or more, with local secondary transformer terminals delivering periodic potential complementary in phase with the periodic potentials delivered by the two distant secondary transformer terminals connected with the two relay terminals.

My invention comprehends, as one means of changing the phase sequence in a given relay, a pole changer or other equivalent device for reversing the connections leading from two of the relay terminals to two of the secondary transformer terminals aforementioned, or otherwise leading into communication with the aforementioned multiphase transmission line.

I will now describe that particular embodiment of my invention which is illustrated in the accompanying drawing. This

drawing diagrammatically represents a single railroad track equipped with a home-and-distant block signaling system.

Two successive signaling apparatuses A and B are represented. The track rails are employed as signal-controlling conductors extending throughout the various signaling blocks or sections, and the rails of successive blocks are insulated from each other by insulations interposed substantially at the signaling posts in the usual manner.

S is a multiphase line generator which in this instance is a triphase generator. The generator S is connected with the triphase transmission line T, U, V, extending along the railway. The signaling apparatuses A and B comprise triphase transformers with primary windings q , q' , respectively, connected to the common transmission line T, U, V. r and r' respectively designate the triphase secondary windings of these transformers. In this instance both the primary and secondary windings are arranged in star form and have their juncture points or middle points connected with a common neutral line wire W which is grounded at x.

The three coils 8, 9, and 10 of the secondary winding r are homologous respectively with the three coils 8^b , 9^b and 10^b of the secondary winding r' ; that is to say, the three triphase periodic potentials of the coils 8, 9 and 10 are in phase respectively with the potentials delivered at the terminals of the coils 8^b , 9^b and 10^b . The terminals of the secondary coils 9 and 10 are connected through the semaphore-controlled pole-changer n , o , with the track rails c , d , of the block next in rear, and the terminals of the secondary coils 9^b and 10^b are similarly connected through the semaphore-controlled pole-changer n' , o' , with the rails c' , d' , of the block A, B, extending next in rear of the signaling apparatus B including such secondary coils 9^b and 10^b .

The signaling apparatuses A and B include triphase relays e and e' respectively. These relays are of one construction, wherefore the relay e may be described to exemplify the relays of the system generally. The relay e comprises a laminated annular magnetic field core f with three coils 14, 15 and 16 in triphase delta coorganization. Concentrically pivoted within the field ring f is a conductive inductor g , which may be made substantially as the squirrel-cage armature of an ordinary rotary-field induction motor. The pivoted inductor g is of course subjected to torque in either direction from a rotary field having a corresponding direction of rotation in the field ring f , but produced therein by triphase current in its triphase windings 14, 15 and 16. A depending pendulum contact finger h secured to the pivoted inductor g tends always to fall by gravity away from its contact stop 19 on the

left hand or from its contact stops 20 and 21 on the right hand so as to assume vertical non-conducting position. Two of the relay terminals are connected by wires 17 and 18 respectively with the rails c' and d' of the block A, B, extending in advance, whereby such relay terminals are connected through such track rails with the terminals of the secondary coils 9^b and 10^b , such connections being subject to reversal, as will be explained hereinafter, by the semaphore-controlled pole-changer n' , o' , of the signaling apparatus B. The remaining terminal of the relay e is connected by a conductor 13 with the terminal of the remaining coil 8 of the secondary winding r . Since the secondary coil 8 is homologous with the secondary coil 8^b , it will be apparent that such connection of the third terminal of the relay e with the terminal of the secondary coil 8 is equivalent to a connection of such third relay terminal with the terminal of the secondary coil 8^b , although the connection of the third relay terminal with the secondary coil 8 through the short-wire 13 avoids the employment of an additional line conductor extending throughout the block A, B, to connect such third relay terminal with the secondary coil 8^b at the advance end of the block. The connections of the relay e' with the track rails of the block next in advance and with the secondary winding r' correspond to the foregoing connections of the relay e .

Normally, that is to say, when there is no train present in any one of the signaling blocks affecting the signaling apparatus, the signals are in their clear positions as indicated in the diagram. The home and distant signals i and j of the signaling apparatus A are held clear through the following agencies. The terminal of the secondary coil 9^b of the signaling apparatus B communicates with one terminal of the triphase relay e through a series of conductors traceable as follows: from the terminal of the secondary coil 9^b through the conductor 12^b, lower contact finger o' of the pole-changer n' , o' , controlled by the home-signal semaphore i' , which contact finger is in contact with its upper stop 3^b when the home signal i' is clear as indicated, and from the contact stop 3^b, through the conductor 2^b, track rail d' of the block B, A, and conductor 18 to one terminal of the triphase relay e . The terminal of the secondary coil 10^b of the signaling apparatus B communicates with a second terminal of the triphase relay e through a series of conductors traceable as follows: from the terminal of the secondary coil 10^b, through the conductor 11^b, upper contact finger n' of the pole-changer n' , o' , which upper finger is in contact with its upper contact stop 4^b, while the home-signal semaphore i' is clear as indi-

cated, and from the contact stop 4^b through the conductor 5^b, track rail c' of the block B, A, and conductor 17 to the second terminal of the triphase relay e. The third 5 terminal of the triphase relay e is connected with the terminal of the coil 8 of the secondary winding r, as already explained. By the foregoing connections the three terminals of the triphase relay e are subjected to triphase 10 potentials producing a triphase counter-clockwise rotating rotary field in the field ring f so as to turn the pivoted inductor g counter-clockwise and bring its pendulum contact finger h into contact with its right hand 15 coöperating contact stops 20 and 21. Thereby local circuits are closed for clearing and holding clear the home and the distant signal semaphores i and j, the home-clearing local circuit being traceable as follows: from 20 one pole of the local battery y, through a wire connection to the pendulum contact finger h and thence through the contact stop 20 and wire connection, to and through the home-signal semaphore-actuating-and-retaining electro-mechanism, and thence back to the opposite pole of the local battery y. The distant-clearing local circuit is traceable as follows: from one pole of the local battery y through wire connection, pendulum contact finger h, contact stop 21, connecting wire, home-signal semaphore-actuating-and-retaining electro-mechanism, and thence by connecting wire back to the opposite pole of the local battery y. The home 35 and distant signals of the signaling apparatus B are cleared and held clear by agencies corresponding to the agencies above described for clearing and holding clear the home and distant signals i and j of the signaling apparatus A.

Now, it will be quite apparent that if a train should enter the block A, B, its wheels and axles would form a low resistance bridge or shunt between the rails c' and d' so as 45 to effectually short-circuit those two terminals of the triphase relay e which are connected with such rails c' and d', whereupon the multiphase relay e would be no longer subjected to multiphase current tending to 50 rotate its pivoted inductor g, so that the pendulum contact finger h would assume its vertical non-contacting position and thus open the local signal-clearing circuits of the local battery y to place the home and 55 distant signals i and j in their danger positions. We may now assume that the train in the block A, B, has passed from such block into the block extending in advance of the signaling apparatus B, whereupon 60 the home and distant signals i' and j' assume danger positions for the same reasons just explained regarding the home and distant signals i and j of the apparatus A. As 65 the home-signal semaphore i' of the signaling apparatus B assumes its danger posi-

tion, the pole-changer actuating foot m' connected with the semaphore is raised from contact with the extension 7^b on the upper contact finger n' of the pole-changer n', o', so that the pole-changer contact fingers n' 70 and o' are no longer held in their upper positions but fall by gravity into their lower positions making contact respectively with the contact stops 3^b and 6^b. This reversal of the pole-changer n', o', obviously reverses 75 the connections leading from the terminals of the secondary coils 9^b and 10^b through the track rails c' and d' to two terminals of the triphase relay e so that as soon as the rear end of a train emerges from the block A, B, 80 the triphase relay e will be again subjected to triphase current but with a sequence of current phases in its triphase coils 14, 15 and 16 different from the phase sequence which obtained with the semaphore-controlled pole-changer n', o', held in its afore-described upper position by clear condition 85 of the home-signal semaphore i' of the signaling apparatus B. This change in phase sequence at the terminals of the triphase 90 relay e effects a reversal in rotative direction of the rotary field produced by the triphase current, that is to say, the field now rotates clockwise instead of counter-clockwise as with the home-signal semaphore i' 95 in clear position, and this clockwise rotation of the rotary field in the triphase relay e develops a clockwise torque in its pivoted conductor g so as to turn such inductor clockwise and move its pendulum contact 100 finger h into contact with its left hand contact stop 19, so as to close a local home-signal clearing circuit traceable as follows: from one terminal of the local battery y, through the connecting wire to the pendulum contact finger h, and thence through the contact stop 19 and connecting wire to and through the home-signal semaphore-actuating-and-retaining electro-mechanism, and thence back to the opposite pole of the 110 local battery y. Closure of the foregoing local circuit of course clears the home signal i and maintains the same in clear position. Now when the train leaves the advance end of the block extending in advance of the 115 signaling apparatus B, the home-signal semaphore i' will be cleared as the home signal i was cleared when the train left the block A, B, and as the home-signal semaphore i' reaches its clear position the pole-changer n', o', controlled thereby will be reversed so as to reestablish in the triphase 120 relay e that sequence and counter-clockwise direction of field rotation which is required to clear both the home and the distant signal semaphores i and j as above described.

It will be apparent that my invention or various features thereof may be embodied in arrangements and constructions specifically quite different from that particular arrange- 125

ment and construction which I have illustrated and described as one embodiment of my invention, such modified embodiments coming, however, wholly within the principles, spirit and scope of my invention.

5 I claim:

1. A railway traffic-controlling system comprising a traffic-controlling apparatus in control of traffic along the railway track, a triphase relay in control of the traffic-controlling apparatus and responsive to a change in phase sequence of triphase alternating or periodic current variations in such relay, means for producing such triphase current variations in the relay, and means for changing the phase sequence of such current variations to actuate the relay and control the traffic-controlling apparatus.
- 10 2. A railway traffic-controlling system comprising a traffic-controlling apparatus arranged in control of traffic along the railway track, a triphase electric relay in control of the traffic-controlling apparatus and differentially responsive to two different phase sequences of triphase current alternations or variations in such relay, means for producing such triphase current variations in the relay with a given phase sequence to effect a given response of the relay, and means for changing the phase sequence of such triphase current variations in the relay to effect a different response of such relay.

3. A railway traffic-controlling system comprising a traffic-controlling apparatus in control of traffic along a railway track, a triphase relay in control of the traffic-controlling apparatus and having three terminals and responsive to a change in phase sequence of triphase alternating or periodic potential variations at such relay terminals, means for effecting such potential variations at such terminals substantially in triphase relation, and means for reversing the connections to two of the relay terminals to change the phase sequence of potential variations at the relay terminals and thus operate the relay to control the traffic-controlling apparatus.

4. A railway traffic-controlling system comprising a traffic-controlling apparatus in control of traffic along a railway track, a triphase electric relay in control of the traffic-controlling apparatus and having three terminals and differentially responsive to different phase sequences of alternating or periodic triphase variations in current potential at such three terminals, means for effecting such triphase potential variations with a given phase sequence at the three relay terminals to effect a given response of the relay, and means for effecting such triphase potential variations with a different phase sequence at the three relay terminals to effect a different response of the relay.

5. A railway traffic-controlling system comprising a traffic-controlling apparatus in control of traffic along the railway track, a triphase relay in control of the traffic-controlling apparatus and having two terminals connected with two of the track rails as conductive leads to such terminals and such relay being responsive to a change in phase sequence of triphase alternating or periodic potential variations at the relay terminals or in the conductive leads connected with such terminals, current-producing means for effecting such potential variations substantially in triphase relation at such relay terminals or in the conductive leads thereto, and means for reversing the connections of the current-producing means to the track rails which constitute conductive leads to two of the relay terminals whereby to change the phase sequence of triphase potential variations at the relay terminals and thereby actuate the relay.

6. A home-and-distant railway block signaling system comprising a home-and-distant signaling apparatus in proximity to a railway track, a triphase relay in control of the distant signal thereof and responsive to a change in phase sequence of triphase currents in the relay, means for supplying triphase currents to the relay, and means for effecting a change in the phase sequence thereof to actuate the relay.

7. A railway block signaling system comprising a home-and-distant signaling apparatus in control of traffic along a railway track, a triphase relay differently responsive to different sequences of triphase current, and means to control the home signal by response of the relay to one phase sequence of triphase currents and to control the distant signal by response of the relay to a different phase sequence of triphase currents, means for supplying triphase currents to the relay, and means for determining the phase sequence of such triphase currents in the relay to determine its actuation.

8. A home-and-distant railway block signaling system comprising a home-and-distant signaling apparatus in control of traffic along a railway track, a triphase rotary-field induction relay including triphase rotary-field coils and a conductive inductor co-active with the rotary-field coils and differently responsive to different sequences of triphase current in the relay, means for supplying triphase currents to the rotary field coils, means for controlling the phase sequence of such currents, means to control the home signal by response of the inductor to one phase sequence of triphase current in the relay, and means to control the distant signal by response of the inductor to another phase sequence of triphase current in the relay.

9. A home-and-distant railway block sig-

- naling system comprising a home-and-distant signaling apparatus in control of traffic along a railway track, a triphase rotary-field induction relay including triphase rotary-field coils and a conductive inductor co-active with the rotary field to be moved in a given direction by a given direction of field rotation and to be moved in the opposite direction by the opposite direction of field rotation and such relay being arranged to control the home signal by one direction of inductor movement and the distant signal by the other direction of inductor movement, means for supplying signal-controlling currents to the rotary-field coils of the relay in triphase relation, and means for determining the phase sequence of currents in such coils to determine the direction of field rotation and the direction of movement of the conductive inductor.
10. A traffic-controlling system comprising a source of multiphase current, a multiphase traffic-controlling current transmission line communicating with the source of multiphase current and extending along the railway, traffic-controlling means located at various traffic-controlling points on the railway, multiphase transformers connected with the transmission line, multiphase relays in control of the traffic-controlling means and in turn controllable by multiphase traffic-controlling current and each responsive to a change in the phase sequence of such multiphase current in such relay and each relay having its terminals connected with secondary transformer terminals all different in phase of potential, and means for reversing the connections to two terminals of each relay to change the phase sequence of multiphase current in the relay and thus effect response of the relay and control the traffic-controlling means governed thereby.
11. A railway traffic-controlling system comprising electrically controllable traffic-controlling means located at various traffic-controlling points on the railway line, a source of multiphase current, a multiphase traffic-controlling current transmission line communicating with the source of multiphase current and extending along the railway, multiphase transformers communicating with the transmission line and each having secondary transformer terminals all different in the phase of their potential, triphase relays in control of the traffic-controlling means and each responsive to a change in phase sequence of triphase current therein, for each relay two conductive connections respectively including two of the track rails and leading from two terminals of the relay to two of the secondary transformer terminals different in phase of potential, additional conductive connections leading from the additional terminals of the relays to respectively secondary terminals different in phase potential from the aforementioned secondary terminals connected through the track rails with the aforementioned relay terminals, and means for reversing the aforesaid conductive relay connections including the track rails whereby to change the phase sequence of triphase currents in the relays and actuate the relays to control the traffic-controlling means respectively governed by such relays.

relays to respective secondary terminals connected through the track rails with the aforementioned relay terminals, and means for reversing the aforesaid conductive relay connections including the track rails whereby to change the phase sequence of multiphase currents in the relays and actuate the relays to control the traffic-controlling means respectively governed by such relays.

12. A traffic-controlling system comprising a source of triphase current, a triphase traffic-controlling current transmission line communicating with the source of triphase current and extending along the railway, traffic-controlling means located at various traffic-controlling points on the railway, triphase transformers connected with the transmission line, triphase relays in control of the traffic-controlling means and in turn controllable by triphase traffic-controlling current and each responsive to a change in the phase sequence of such triphase current in such relay and each relay having its terminals connected with secondary transformer terminals all different in phase of potential, and means for reversing the connections to two terminals of each relay to change the phase sequence of triphase current in the relay and thus effect response of the relay and control the traffic-controlling means governed thereby.

13. A railway traffic-controlling system comprising electrically controllable traffic-controlling means located at various traffic-controlling points on the railway line, a source of triphase current traffic-controlling current transmission line communicating with the source of triphase current and extending along the railway, triphase transformers communicating with the transmission line and each having three secondary transformer terminals all different in the phase of their potential, triphase relays in control of the traffic-controlling means and each responsive to a change in phase sequence of triphase current therein, for each relay two conductive connections respectively including two of the track rails and leading from two terminals of the relay to two of the secondary transformer terminals different in phase of potential, additional conductive connections leading from the additional terminals of the relays to respectively secondary terminals different in phase potential from the aforementioned secondary terminals connected through the track rails with the aforementioned relay terminals, and means for reversing the aforesaid conductive relay connections including the track rails whereby to change the phase sequence of triphase currents in the relays and actuate the relays to control the traffic-controlling means respectively governed by such relays.

14. A railway traffic-controlling system comprising traffic-controlling means located at a given traffic-controlling point on a railway, a multiphase relay in control of the traffic-controlling means and in turn controllable by multiphase current, a distant source of periodic potentials of two different phases constituting two phases of the multiphase potential for the relay, two conductors leading from two terminals of the relay to such source, and, connected with the relay, local means for producing periodic potential complementary to the two phases of periodic potential delivered by the distant source so as to complete the phases of the multiphase relay current, and means for controlling the multiphase current.
15. A railway traffic-controlling system comprising traffic-controlling means in control of traffic at successive traffic-controlling points on the railway track, a source of multiphase current, a multiphase traffic-controlling current transmission line communicating with the source of multiphase current and extending along the railway, a number of multiphase transformers located at the traffic-controlling points and connected with the transmission line and having secondary multiphase terminals, multiphase relays located at the traffic-controlling points and in control of the traffic-controlling means, conductors leading from two terminals of each multiphase relay to two secondary terminals of the transformer at a distant traffic-controlling point, conductors leading from the remaining terminals of the relays to the remaining secondary terminals of the transformers collocated with such relays respectively.
16. A railway traffic-controlling system comprising traffic-controlling means located at successive traffic-controlling points on a railway track, a source of multiphase current, a multiphase traffic-controlling current transmission line communicating with the source of multiphase current and extending along the railway, multiphase transformers located substantially at the various traffic-controlling points and communicating with the multiphase transmission line and having multiphase secondary terminals, multiphase relays located at the various traffic-controlling points and in control of the traffic-controlling means at such points, from two terminals of each relay two conductors including the two track rails and leading to two secondary terminals of the transformer located at a distant traffic-controlling point, and conductors leading from the remaining terminals of the multiphase relays to the remaining secondary terminals of the transformers collocated with such relays respectively.

In testimony whereof I affix my signature in presence of two witnesses.
